UNITED STATES PATENT OFFICE

2,459,610

GOLF SHOE SPIKE OR CALK

Arthur F. Zadina, Long Island City, N. Y.

Application May 5, 1947, Serial No. 746,139

10 Claims. (Cl. 36—67.5)

1

This invention appertains to novel and useful improvements in athletic foot wear, particularly that utilized in the active engagement of golf or similar sports.

An object of this invention is to provide improved golf shoe spikes, characterized by means for retaining said spike within the sole of a shoe without utility of peening, riveting or the like.

Another object of this invention is to provide means for retaining the stud of the spike in a selected adjusted position.

Another object of the present invention is to provide means for tightening said spike entirely from the exterior of the shoe utilizing the invention.

A further object of this invention is to provide an improved device of the character described which is inexpensive, commercially feasible and exceedingly satisfactory in its intended operation.

Ancillary objects and features of novelty shall become apparent to those skilled in the art, in following the description of the preferred embodiment of the present invention illustrated in the accompanying drawings, wherein:

Figure 1 is a perspective view of a shoe utilizing the preferred form of the present invention;

Figure 2 is a plan view of a spike forming part of the improved shoe mentioned above;

Figure 3 is a sectional view of the invention disclosed in Figure 2 and taken substantially on the line 3—3 thereof and in the direction of the arrows;

Figure 4 is a transverse section of the detail of construction disclosed in Figure 3 and taken substantially on the line 4—4 thereof and in the direction of the arrows;

Figure 5 is an exploded view of the elements forming the preferred form of the present invention;

Figure 6 is an elevational front view of the tightening tool used in conjunction with this invention;

Figure 7 is a transverse sectional view of the detail of construction disclosed in Figure 5 and taken substantially on the line 7—7 thereof and in the direction of the arrows;

Figure 8 is a fragmentary sectional view of the detail disclosed in Figure 4 and taken substantially on the line 8—8 thereof and in the direction of the arrows;

Figure 9 is a bottom view of the tool disclosed in Figure 6 and taken substantially on the line 9—9 thereof and in the direction of the arrows; and

Figure 10 is a perspective view of a second tool

2

used in conjunction with the operation of the preferred form of this invention.

Referring now in detail to the illustrated preferred embodiment of the present invention, like reference characters are used throughout to indicate similar elements thereof.

This invention has been developed to provide a device for improving golf shoes and the like and for rendering conventional golf shoes more comfortable even after constant wear begins to render portions of the shoe old and partially worn out. It is well known to those skilled in the art that golf shoes tend to curl after a duration and further, the golf spikes become loose, uncomfortable and even pull out of the surrounding leather. This invention provides means for periodically tightening golf spikes without recourse to the inner portion of the shoe and further, without utilizing the conventional, undesirable peened edges.

A conventional golf shoe, generally indicated by the reference numeral 10 is provided with the usual apertures 12 therein. These apertures are provided for the purpose of receiving golf spikes therein and may be conventional in number. The improvement characterized by the present invention resides in the construction of the golf shoe spikes. The said improved spikes are composed of only three elements, disclosed best in Figure 5. A first collar 14 has a sleeve 16 secured thereto, or, if desired, integral therewith. This sleeve 16 is received in the aperture 12, disclosed in Figure 3.

A second collar 18 having apertures 20 adjacent the periphery thereof is provided with a sleeve 22 integral therewith. This last mentioned sleeve 22 is engageable with the outer surface of the said sleeve 16. A lug 24, conventional in configuration, is provided with the usual threaded shank 26 thereon. Now, the interior or bore of the said sleeve 16 is provided with complementary threads 28 for the purpose of retaining the entire assembly in fixed, predetermined position.

As is apparent from an inspection of Figure 3, the sleeve 16 is received in the aperture 12, provided in the shoe sole 30. The interior liner 32 is provided over the sleeve 16 and its associated collar 14 after the same is placed in the desired position. Then, the collar 18 and its associated sleeve 22 is placed from the outside of the sole 30, within the said aperture 12. It is noted at this point that the preferable exterior configuration of each of the said collars 16 and 22 respectively is polygonal. By this construction, the said col-

lars 16 and 22 are held immovable rotatably, relative to each other.

Then, the said stud 24 is received in the sleeve 22, thence in the threaded interior portion of the collar-sleeve member 14, 16. When it is found desirable to tighten the stud 24, a tool 35 having studs 36 extending therefrom is utilized. These studs 36 are engageable with the slots 37 for holding the same in a fixed position. Then, a second tool having an annulus 40 thereon is provided for the purpose of holding or grasping in the aperture 20 of the collar 18. This last mentioned tool 38 is adapted to be received over the tool 35 in this operation. Also, protuberances 42 are on said annulus 40 for the purpose of holding in the apertures 20 during the tightening operation.

Lugs 43 extend from said collar 18 and are engageable with the said slots 37 in said stud 24. The said locking means 43 engage selected slots 37 insuring against undesirable rotation of the threaded shank 26 within the bore of the sleeve 16.

Having thus described this invention, it is apparent that a structure capable of performing all of the specifically mentioned objects as well as numerous other objects is set forth. However, it is apparent to those skilled in the art that various changes including omissions, additions and rearrangement of elements may be made herein without departing from the spirit of the invention. Accordingly, limitation is sought only in accordance with the scope of the following claims.

The invention thus described, what is claimed as novel and improved is as follows:

1. A golf shoe spike comprising a threaded stud having an enlargement thereon, a collar adapted to seat in the sole of a shoe, a noncircular sleeve on said collar, a second collar adapted to seat in the sole of a shoe having a second noncircular sleeve received on said first mentioned sleeve, threads in said first sleeve engageable with the threads of said stud, means for grasping said second collar, means for grasping said stud, latch means on said second collar engageable with said stud grasping means.

2. The construction recited in claim 1, said collar grasping means comprising apertures therein.

3. The construction recited in claim 2, said stud grasping means comprising slots in said enlargement.

4. The construction recited in claim 3, said latch means comprising protuberances on said first collar engageable with said slots.

5. In a sportsman's shoe, a first collar having a first noncircular sleeve thereon adapted to extend in an aperture in the sole of a shoe, a second

collar having a second noncircular sleeve thereon received on said first sleeve, a stud in said first sleeve, friction means for retaining said stud in said first sleeve, means for grasping said second collar, means for grasping said stud, whereby said first collar may be held during rotation of said stud.

6. The construction recited in claim 5 and means for locking said stud and second collar in selected positions.

7. The construction recited in claim 6, said locking means including protuberances on said second collar engageable with said second collar grasping means.

8. A sportsman's shoe attachment comprising a first collar having an integral inner sleeve with at least one flat side, said inner sleeve being internally threaded, a second collar having spaced apertures therein, an outer sleeve having at least one flat side secured to said second collar, said outer sleeve being slidably received on said inner sleeve, a stud having an integral enlargement and slots therein, said stud threadedly received in the threaded bore of said inner sleeve, resilient means associated with said first collar lockingly engaging said slots.

9. The combination of claim 8 and said resilient means comprising at least one prong projecting from said first collar whereby said slots cooperating with said prong lock said sleeves in fixed position.

10. A golf shoe spike comprising a stud having an enlargement with slots therein, a first collar engaging the under surface of said enlargement, a substantially rectangular outer sleeve attached to said first collar, a second collar, a substantially rectangular inner sleeve attached to said second collar slidably received within the bore of said first mentioned outer sleeve, said stud having a threaded shank adjustably received within the bore of said inner sleeve, and a resilient prong integral with said first collar engaging said slots to lock said sleeves and stud in assembled position entirely from one side of the first collar.
